CLAIM

The ornamental design for a pot lid holder, as shown and described.

DESCRIPTION

FIG. 1 is a front perspective view of a pot lid holder, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines in the figures are for the purposes of illustrating portions of the pot lid holder and form no part of the claimed design.

1 Claim, 8 Drawing Sheets
